LOOM BATTERY THREAD TENSIONER

Marvin W. Odom, Roswell, and Thomas B. Hunt,
Atlanta, Ga.

Application January 15, 1953, Serial No. 331,366

7 Claims. (Cl. 139—248)

This invention relates to the production of textile fabrics and more particularly to looms employed in such manufacture. The invention is especially concerned with the maintenance of the proper tension on the yarn at all times and particularly during the time of the transfer of bobbins when the thread becomes exhausted from one and another bobbin is transferred to the shuttle.

With loom equipment in use heretofore, the yarn has not been maintained at the proper tension at all times and a mispick has resulted with consequent imperfections in the fabric on account of the thread sagging due to the vibration of the loom or the failure of the attendant to wind the yarn about the tension knob adjacent the tension disk associated with the battery.

It is an object of the invention to overcome the deficiencies in the mechanism which previously has been employed and to eliminate the human element and its failure to properly tension the yarn by providing mechanism which will maintain the proper tension on the yarn at all times so that the fabric will be devoid of imperfections.

Another object of the invention is to provide the necessary tension on yarn carried in a battery by the use of mechanical tensioning means which is fully automatic in its operation and which is capable of accommodating from the lightest to the heaviest and from the weakest to the strongest of yarns.

Another object of the invention is to improve the cleanliness of the loom by keeping waste yarn severed by the yarn cutter off of the lay as the battery of bobbins is rotated, the yarn being held by the tension mechanism from one side of which the surplus yarn can be detached by the attendant.

A further object of the invention is to improve the efficiency of the loom by reduction in stoppage occasioned by improper transfer or mispick and to thereby increase production in making it possible for an attendant to care for from 10 to 30 per cent more batteries, particularly in view of the fact that the attendant does not have to wrap the yarn around the tension knob, thus saving labor.

A still further object is to provide automatic mechanical tensioning mechanism comprising cooperating tensioning disks arranged in a series of pairs held in contact under predetermined tension by cone-type tension springs having requisite hardness and durability, and with the springs held in a manner to permit variation of the tension on the yarn.

Further objects and advantages of the invention will be apparent from the following description taken in conjunction with the accompanying drawing, wherein:

Fig. 1 is a perspective illustrating the invention applied to a conventional loom;

Fig. 2, an end elevation of the tensioner per se;

Fig. 3, a section on line 3—3 of Fig. 2; and

Fig. 4, a section through a pair of tensioning disks.

Briefly stated, the invention comprises a yarn-tensioning device which replaces the disk and wrap-around

2

knob used in conjunction with a battery of yarn-carrying bobbins of a conventional loom, by means of which tension is maintained on the yarn during changeover from a bobbin from which the yarn is being exhausted to a full bobbin, the battery on which the bobbins are carried being rotated a fraction of a revolution from one bobbin to the next. The yarn-tensioning member of the present invention comprises a wheel or spider having a hub with 45° arms supporting a ring or annulus upon which cooperating friction disks are mounted in pairs. The contacting disks have peripheral beveled portions to provide a V-shaped groove for yarn receiving, and the disks are maintained in contact by means of cone-type springs. Thus yarn will be gripped between each pair of disks and will not require the wrap-around knob as in prior constructions.

With continued reference to the drawing, a loom 10 is employed for weaving fabric 11 from yarn carried on bobbins 12 supported in a battery 13 mounted on a shaft 14, all of conventional character. The bobbins 12 are taken in a conventional manner from the bottom of the battery, one by one, into the shuttle (not shown) and carried across the width of the fabric being produced until such time as the yarn on the particular bobbin 15 is exhausted. When the yarn is exhausted from one bobbin the battery is rotated a part of a revolution until another bobbin is in the proper position and a changeover from the empty bobbin to the full bobbin is effected.

In the operation just described with apparatus previously in use and in order to produce fabric of top quality, it has been necessary and an attempt has been made to maintain the yarn at the proper tension at all times by extending the same over the periphery of a disk (not shown) and for an attendant to wind the yarn 35 a few turns about a knob (not shown) at the center of the disk. This has resulted in a waste of a large amount of yarn.

The present invention maintains the necessary tension upon the yarn by the provision of yarn tensioning mechanism, comprising a wheel or spider having a hub 15 adapted to be attached to the shaft 14 by an Allen nut 16. The hub is provided with a series of arms 17 of which four are shown, and these arms extend each at an angle substantially of 45° from the axis of the hub and they support at their outer ends a ring or annulus 18. On the ring 18 is a series of spaced outwardly extending radial projections 19 in each of which is mounted a stud 20 disposed substantially at right angles thereto and substantially in the plane of the ring.

On each stud is rotatably mounted a pair of tension disks 21, each having a peripheral beveled portion 22 which constitutes with the beveled portion of the companion disk an annular V-shaped yarn receiving groove.

The adjacent flat side faces of each pair of disks are normally maintained in contact by cone-type, tempered, compression springs 23 mounted on the studs 20 so that yarn can be applied to the groove and thence between the faces of the disks and gripped sufficiently to maintain proper tension thereon. The disks 21 preferably are cup-shaped in order to accommodate the conical tempered compression springs 23 and adjusting nuts 24 threaded on the free end of the studs 20.

It will be understood that the spider of the present invention includes an annulus located substantially in the same position as the notched disk which it replaces and eliminates the necessity for the knob at the center, and in substantially the plane of the disk, as well as the necessity for the attendant winding the yarn about said knob and resulting in a very substantial saving in yarn. Further, elimination of the operation by the attendant or the human element reduces likelihood of improper tensioning of the yarn and fabric of inferior quality. While plastic,

3

which insulates against electricity either static or otherwise, has been found to be satisfactory, the invention is not limited thereto as other materials may be used.

The use of disks in the manner described affords greater ease, flexibility, accuracy and efficiency of operation.

It will be obvious to those skilled in the art that various changes may be made in the invention without departing from the spirit and scope thereof, and therefore the invention is not limited by that which is shown in the drawing and described in the specification, but only as indicated in the appended claims.

What is claimed is:

1. In a loom including a shaft and a battery of bobbins with filling yarn thereon, yarn tensioning mechanism comprising a wheel having a hub of a size to fit on said shaft, and a series of uniformly spaced arms extending at angles of substantially 45° from the axis of said hub, a ring on the outer end of said arms, a series of uniformly spaced radial projections in substantially a single plane extending outwardly from said ring, a stud carried by each of said projections substantially at right angles thereto and in the plane of said ring, a pair of cooperating plastic tension disks with adjacent peripheral portions beveled and providing an annular V-shaped groove mounted on each stud, an adjusting nut retaining each pair of disks on its supporting stud, and a cone-type tempered compression spring urging each pair of disks in contact, one with the other, in a manner to grip yarn when it is placed between them.

2. In a loom including a shaft and a battery of bobbins with filling yarn thereon, yarn tensioning mechanism comprising a wheel having a hub of a size to fit on said shaft, and a series of uniformly spaced arms extending at angles of substantially 45° from the axis of said hub, a ring on the outer end of said arms, a series of uniformly spaced radial projections extending outwardly from said ring, a stud carried by each of said projections substantially at right angles thereto, a pair of cooperating tension disks with adjacent peripheral portions beveled and providing an annular V-shaped groove mounted on each stud, an adjusting nut retaining each pair of disks on its supporting stud, and a cone-type tempered compression spring urging each pair of disks in contact, one with the other, in a manner to grip yarn when it is placed between them.

3. In a loom including a shaft and a battery of bobbins with filling yarn thereon, yarn tensioning mechanism comprising a hub of a size to fit on said shaft, and a series of uniformly spaced arms extending at angles of substantially 45° from the axis of said hub, a ring on the outer end of said arms, a series of uniformly spaced radial projections extending outwardly from said ring, a stud carried by each of said projections substantially at right angles thereto, a pair of cooperating tension disks with adjacent peripheral portions beveled and providing an annular groove mounted on each stud, an adjusting nut retaining each pair of disks on its supporting stud, and a cone-type compression spring urging each pair of disks

in contact, one with the other, in a manner to grip yarn when it is placed between them.

4. In a loom including a shaft and a battery of bobbins with filling yarn thereon, yarn tensioning mechanism comprising a ring mounted concentric to and spaced from the battery, a series of projections mounted on said ring, a pivot member carried by each projection extending laterally from said projection in substantially the plane of the periphery of said ring, a pair of rotatable cooperating tension disks mounted on each pivot member and having adjacent peripheral portions beveled providing an annular groove, an adjustable member retaining each pair of disks on said pivot member and a cone-type compression spring urging the disks of each pair together in a manner to grip yarn.

5. For use with a loom having a shaft and a battery of bobbins with filling yarn thereon, of yarn tensioning mechanism comprising a wheel adapted to fit on said shaft, a series of uniformly spaced supporting projections extending radially outward from said wheel, a pivot member for each of said projections extending laterally therefrom and in substantially the plane of the periphery of said wheel, a pair of cooperating pressure disks rotatably mounted on each pivot member, a cone-type compression spring urging said disks together in a manner to grip yarn.

6. A device for maintaining tension on yarn carried in a battery in connection with a loom, said device comprising a wheel, a hub, a series of spokes and a ring member at the end of said spokes, a series of radial projections extending outwardly from said ring member, a series of studs extending laterally from said projections substantially in the plane of said ring member, and pairs of cooperating friction disks mounted on each stud and having contiguous peripheral edges beveled for guiding yarn between the same mounted on said studs, a conical spring pressing said disks toward each other, and a threaded nut on each of said studs for adjusting the pressure on said spring.

7. A device for maintaining tension on yarn carried in a battery in connection with a loom, said device comprising a circular member, a series of radial projections extending outwardly from said circular member, a series of studs extending substantially laterally from said projections substantially at right angles to the axis of said circular member, pairs of cooperating pressure disks mounted on said studs and adapted to frictionally hold yarn therebetween and spring means forcing said disks together.
